TOY VEHICLE STATION

Robert K. Ostrander, Jr., East Aurora, N.Y., assignor to Fisher-Price Toys, Inc., East Aurora, N.Y., a corporation of New York

Filed Jan. 12, 1966, Ser. No. 580

Term of patent 14 years

(Cl. D34—15)

FIG. 1

FIG. 4

FIG. 1 shows a perspective view of a toy vehicle station showing my new design with one of the dumpers in a tilted position and the gas pump in position for use;

FIG. 2 is a front view with the dumper and pump returned to rest position;

FIG. 3 shows a rear view thereof;

FIG. 4 shows a top view thereof;

FIG. 5 shows a side view thereof taken from the right of FIG. 1; and

FIG. 6 shows a side view thereof taken from the left of FIG. 1.

I claim:
The ornamental design for a toy vehicle station, substantially as shown and described.
